UNITED STATES PATENT OFFICE.

AUGUST J. IMHOFF, OF NEWARK, NEW JERSEY, ASSIGNOR TO J. S. MUNDY HOISTING ENGINE CO., A CORPORATION OF NEW JERSEY.

SWINGING DRUM FOR HOISTING ENGINES.

1,419,855.

Specification of Letters Patent. Patented June 13, 1922.

Application filed August 11, 1921. Serial No. 491,426.

To all whom it may concern:

Be it known that I, AUGUST JOHN IMHOFF, of the city of Newark, county of Essex, State of New Jersey, and a citizen 5 of the United States, have invented certain new and useful Improvements in Swinging Drums for Hoisting Engines, of which the following is a specification.

This invention relates, generally, to hoisting engines, and the object is to provide an 10 improved form of drum particularly intended for use in controlling the mast of a derrick, the mast-turning rope being secured to the drum and being connected with the 15 mast. However, the drum of my invention is obviously applicable to a wide range or field of uses, and is not by any means confined in its application to hoisting-engines.

The object is, more specifically, to improve 20 the form of mast-turning drum disclosed in United States Letters-Patent No. 772,639, granted October 18, 1904, to James N. Wright, assignor to Joseph S. Mundy, for improvements in hoisting engines.

25 The purpose of the present improvements is to provide a drum peculiarly formed to permit of taking up slack in the mast-turning rope, and to provide such drum, in two sections, with novel means for adjusting said 30 sections toward and away from each other, to take up wear in the frictional cone-clutches engageable with said drum.

The invention, in its preferred form, is 35 clearly exemplified in the accompanying drawing, in which like reference characters indicate corresponding parts throughout the several views. Briefly described:

Figure 1 is a longitudinal, diametric sectional view through a drum constructed in 40 accordance with my invention;

Figure 2 is a view in end elevation, looking at the right-hand end of Fig. 1; and

Figure 3 is a detached, detail view, in 45 side elevation, partly broken away and partly in section, of one of the sleeve or coupling-member sections.

Referring, now, in detail to the drawing:

As shown, the drum is in two sections 1 and 2, each provided with an axial bore 3 for the reception of a shaft on which the 50 drum is loosely and slidably mounted, as disclosed in said patent.

Each of said drum-sections is provided with a lateral, circumferential flange 3' 55 hollowed out on its outer side or face, and

having the circumferential wall of its chamber reversely conical, as shown at 4, thus forming a clutch face for engagement with a friction cone, as shown and described in said patent.

60 The two drum-sections are axially aligned and of the same diameter, and are provided, at adjacent ends, with exterior right and left hand threads 5; for instance, the threads on the section 1 may be left hand threads, and those on the section 2 right hand threads, or vice versa.

Uniting the drum-sections, at adjacent 65 ends, is a coupling member or screw-collar, in two sections, 6, 6, screwed on the threaded ends of said drum-sections,—one of said 70 collar-sections 6 on each drum-section. Each of said collar-sections 6 is provided, laterally, with a circumferential flange 6', provided, near its outer or free edge, with an 75 annular series of equidistantly-spaced bolt-holes 7. In assembled position, the collar-flanges 6' are adapted to abut, face to face, and two or more bolts (two being shown in the drawing), 8, 8, are adapted to be passed 80 through aligned apertures 7 in said flanges, and nuts 9, 9 on the threaded ends of said bolts normally secure the bolts in position and the collar-sections 6, 6 against relative movement.

85 Each of said collar-flanges 6' is provided, peripherally, with equidistantly-spaced notches 6^a.

Each of said collar-sections 6, 6 is provided with one or more bosses (one being 90 shown in the drawing), 6^b, drilled to provide a threaded hole 6^c therethrough, in which a screw 6^d may be threaded to bear against the corresponding drum-section 1 or 2, and thus frictionally hold said collar-sections 6, 6 and said drum-sections 1 and 2 95 against relative movement.

The drum-section 2 is provided, peripherally, with radially-extending recesses 2', preferably three in number.

100 Means are provided to prevent independence of rotation of said drum-sections 1 and 2. To this end, they are provided, at adjacent ends, with longitudinally-extending recesses 10, an annular series thereof being 105 provided in the drum-section 2, and two of such recesses in the drum-section 1.

Slidably fitting in pairs of registering recesses 10 are dowel-pins, two being shown, as an example, in the drawing and identified 110

by the reference-numerals 11, 11. As shown, each pin is of a length somewhat less than the combined length of the two registering recesses 10, 10, in which it is seated, but 5 greater than the length of a single opening 10. The length of the pins relative to the alined recesses in which they slide is such that, when they are moved to the limit of their travel to the left in Fig. 1, from the 10 position in which they are shown in said figure, they will be free of the openings in the drum-section 2.

The drum-section 1 is cut away longitudinally and peripherally, as shown at 12, 15 12, so as to provide two slots or openings communicating with the two recesses 10, 10, in said drum-section, said cut-away portions extending from a point in proximity with one end of said two recesses and terminating 20 short of the adjacent end of said drum-section 1.

A plug or cap 13 for each of said cut-away portions 12 is provided, each of said plugs normally resting upon the corresponding pin 11, thereby limiting inward movement of said plug in the recess 10. A screw 14 passing transversely through each of said caps or plugs and seated at its inner end in 25 said drum-section 1 holds the plug in position. The heads of the screws are countersunk in the drum-section 1, as shown.

A screw 15 is adapted to pass transversely through each of the pins 11, its head normally being seated in one end of the cut-away portion 12.

Preferably, the screws 6^a bear against the drum-sections 1 and 2 through an interposed plug 6^e (one for each screw), as shown in Fig. 3.

40 In operation, to take up slack in the mast-turning rope: The bolts 8, 8 are removed; the screw-studs 14, 14 are unscrewed, and the plugs 13, 13 removed from the angular extensions 12, 12 of the recesses 10, 10; the 45 screw-studs 15, 15 are unscrewed about three-fourths of an inch, so that the outer ends thereof project beyond the periphery of the drum, whereupon, using these projecting ends as finger-holds, the operator slides the pins 11, 11 to the left in Fig. 1, so that they 50 clear the openings or recesses 10 in the drum-section 2, which drum-section can now be turned. The operator thereupon places a steel bar in one of the holes 2' in said drum-section 2, and turns said drum-section until, say, the two openings 10 next succeeding the two openings in said drum-section in which the bolts 11, 11 had just been withdrawn are 55 in register with the two recesses 10, 10 in the drum-section 1; whereupon the bolts 11, 11 are moved into said two registering recesses 10, 10 in the drum-section 2, the studs 15, 15 are screwed in until their outer ends 60 are flush with the drum-periphery, the plugs 65 13, 13 are replaced, the plug-screws 14, 14

screwed into operative position, and the bolts 8, 8 replaced.

The operation of spreading the drum-sections apart, to take up wear in the wood friction-cones engaging the cone-surfaces 4, 70 4, is as follows: The set-screws 6^a, 6^a are loosened; then a bar is placed in one of the slots 6^a and the operator, standing at the front of the engine, turns the collar 6'-6' 75 towards himself until the desired adjustment is attained, whereupon the set-screws 6^a, 6^a are tightened and the bar removed from the slot 6^a.

The advantages of my invention will be 80 obvious, especially to those skilled in the art to which it pertains. Changes may be made in the physical embodiment shown, within the scope of the appended claims, without departing from the spirit of my invention, or necessarily sacrificing any of its 85 advantages.

Having thus fully described my invention, what I claim as new and desire to secure by Letters-Patent is:

1. A drum in two axially-alined sections, 90 the adjacent ends thereof having longitudinally-extending recesses, an annular series thereof being provided in one drum-section and two of such recesses in the other drum-section, said two recesses having, each, at 95 its inner end, an offset, angular portion extending through the periphery of said drum-section, and said two recesses being adapted to register with two of the recesses in said annular series, two bolts slidably mounted in the two pairs of registering recesses, a plug 100 removably seated in each of said angular, offset portions of said two recesses and bearing against said bolts for normally holding them against longitudinal movement, and means for normally holding said drum-sections against relative longitudinal movement.

2. A drum in two axially-alined sections, 110 the adjacent ends thereof having longitudinally-extending recesses, an annular series thereof being provided in one drum-section and two of such recesses in the other drum-section, said two recesses having, each, at 115 its inner end, an offset, angular portion extending through the periphery of said drum-section, and said two recesses being adapted to register with two of the recesses in said annular series, two bolts slidably mounted in the two pairs of registering recesses, a 120 plug removably seated in each of said angular, offset portions of said two recesses and bearing against said bolts for normally holding them against longitudinal movement, screws passing through said plugs for removably holding them against displacement, and means for normally holding said drum-sections against relative longitudinal movement.

3. A drum in two axially-alined sections, 130

the adjacent ends thereof having longitudinally-extending recesses, an annular series thereof being provided in one drum-section and two of such recesses in the other drum-section, said two recesses being adapted to register with two recesses in said annular series, two bolts slidably mounted in the two pairs of registering recesses, members carried by said bolts and projecting therefrom and adapted to be used by the operator in sliding said bolts, means for normally holding said drum-sections against relative longitudinal movement, and means for normally holding said bolts against longitudinal movement.

4. A drum in two axially-aligned sections, the adjacent ends thereof having longitudinally-extending recesses, an annular series thereof being provided in one drum-section and two of such recesses in the other drum-section, said two recesses being adapted to register with two recesses in said annular series, two bolts slidably mounted in the two pairs of registering recesses, threaded studs screwed into said bolts and adapted to be used by the operator in sliding said bolts, means for normally holding said drum-sections against relative longitudinal movement, and means for normally holding said bolts against longitudinal displacement.

5. In hoisting-apparatus, the combination of a hoisting drum in two axially-aligned sections exteriorly threaded at adjacent ends, the threads on one of said ends being right-hand threads and those on the other end being left-hand threads, and means for effecting, independently, either an adjustment of said drum-sections axially toward and away from each other, or a rotatable adjustment of one of said drum-sections with reference to the other drum-section, and comprising a screw-collar in two sections, one of which is screwed on one of said threaded ends, and the other of which is screwed on the other threaded end, and means for normally holding said screw-collar sections against relative rotation.

6. In hoisting-apparatus, the combination of a hoisting drum in two axially-aligned sections exteriorly threaded at adjacent ends, the threads on one of said ends being right-hand threads and those on the other end

being left-hand threads, and means for effecting, independently, either an adjustment of said drum-sections axially toward and away from each other, or a rotatable adjustment of one of said drum-sections with reference to the other drum-section, and comprising a screw-collar in two sections, one of which is screwed on one of said threaded ends, and the other of which is screwed on the other threaded end, and bolts connecting said screw-collar sections.

7. In hoisting-apparatus, the combination of a hoisting drum in two axially-aligned sections exteriorly threaded at adjacent ends, the threads on one of said ends being right-hand threads and those on the other end being left-hand threads, and means for effecting, independently, either an adjustment of said drum-sections axially toward and away from each other, or a rotatable adjustment of one of said drum-sections with reference to the other drum-section, and comprising a screw-collar in two flanged sections, one of which collar-sections is screwed on one of said threaded ends, and the other of which collar-sections is screwed on the other threaded end, and bolts passing through the flanges of said collar-sections.

8. In hoisting-apparatus, the combination of a hoisting drum in two axially-aligned sections exteriorly threaded at adjacent ends, the threads on one of said ends being right-hand threads and those on the other end being left-hand threads, and means for effecting, independently, either an adjustment of said drum-sections axially toward and away from each other, or a rotatable adjustment of one of said drum-sections with reference to the other drum-section, and comprising a screw-collar in two flanged sections, one of said collar sections being screwed on one of said threaded ends, and the other collar section being screwed on the other threaded end, the flanges of said collar-sections being provided with marginal notches, and means for normally holding said screw-collar sections against relative rotation.

In testimony whereof I hereunto affix my signature.

AUGUST J. IMHOFF.
